HARRY GOLDBERG,
INVENTOR,

BY

James A. Rechelby

ATTORNEY

UNITED STATES PATENT OFFICE

145,598

DESIGN FOR A COAT

Harry Goldberg, New York, N. Y.

Application May 29, 1946, Serial No. 130,215

Term of patent 3½ years

(CL. D3—4)

To all whom it may concern:

Be it known that I, Harry Goldberg, a citizen of the United States of America, residing in New York city, county of New York, and State of New York, have invented a new, original, and ornamental Design for a Coat, of which the following is a specification, reference being had to the accompanying drawing, forming part thereof, wherein,

I claim:

The ornamental design for a coat, substantially as shown.

HARRY GOLDBERG.
